Primary Examiner — Kendra Leslie Hamilton*Assistant Examiner* — Amanda Christensen(74) *Attorney, Agent, or Firm* — Norton Rose Fulbright US LLP(57) **CLAIM**

The ornamental design for a sample processing instrument, as shown and described.

DESCRIPTION

FIG. 1 is a top, front, left side perspective view of a sample processing instrument showing my new design;

FIG. 2 is a top, back, right side perspective view thereof;

FIG. 3 is a front elevation view thereof;

FIG. 4 is a back elevation view thereof;

FIG. 5 is a right side elevation view thereof;

FIG. 6 is a left side elevation view thereof; and,

FIG. 7 is a top plan view thereof.

In the drawings, the broken lines depict portions of the sample processing instrument that form no part of the claimed design.

1 Claim, 7 Drawing Sheets(56)
